UNITED STATES PATENT OFFICE.

ELIZABETH ROWLAND, OF LONDON, ENGLAND.

INHALER.

SPECIFICATION forming part of Letters Patent No. 627,928, dated June 27, 1899.

Application filed June 7, 1897. Serial No. 639,774. (No model.)

To all whom it may concern.

Be it known that I, ELIZABETH ROWLAND, a subject of the Queen of Great Britain and Ireland, residing at 15 Old Cavendish street, 5 Cavendish Square, London, England, have invented certain new and useful Improvements in and Connected with Medical Inhalers with or without a Thermometer Attached Thereto, as desired, of which the following is a specification.

My object in attaching a thermometer to my inhaler is to assist patients to keep their apartments at a reasonable or desired temperature, which should not usually exceed 65° 15 Fahrenheit. In this many people err greatly and badly-ventilated apartments and heavy wearing-apparel result. I therefore provide means to enable people to judge for themselves, and thus make the necessary arrangements for their own comfort.

To clearly explain my invention, reference is made to the accompanying drawings, which form part of this specification.

The inhalers are made of silver or some 25 such suitable material and of a circular form somewhat in the shape of a watch. The thermometer is likewise in the form of a ring, which is sunk into and secured in a correspondingly-shaped hollow in the front of the 30 inhaler by means of a small spring *a*, as shown in Figure 1, and detached from the inhaler, as shown in Figs. 2 and 3, when it is required for use in taking the temperature of a patient.

35 The inhaler is made about two and one-half inches in diameter and about one inch in depth. Fig. 4 shows a sectional elevation in the line A B of Fig. 2. Fig. 5 is a back view. The back is usually hard-soldered to 40 the sides, in which one or two outlets are provided, as shown at A A. The outlets are internally screw-threaded to take a screw-stopper provided with a rubber washer *G* to prevent any evaporation from the inhaler. Over

45 the lower ends of said outlets are pieces of wire-gauze *C*, soldered from side to side of the inhaler immediately beneath the outlets to retain the absorbent material *D*—such as sponge, prepared wool, or asbestos—with 50 which the inhaler is closely packed. A small circular case *E* is sunk in the center of the front of the inhaler and soldered thereto.

The inhaler may be constructed in a less expensive metal if a cheaper article be required. The thermometer is sunk in the recess in the 55 front of the inhaler and retained in position by means of a small pin. The thermometer may be either that of the "Immisch" kind, as described in British Patent No. 953, A. D. 1881, or I may use my improved mercury thermometer, made about an inch in diameter and of a circular form. The thermometer is sunk to the level of the dial, and in some cases the bulb is sunk beneath the level of the dial. The dial rests on a beveled ledge sunk in the 65 front of the inhaler, and when the whole is fastened in position the inhaler has the appearance of a watch. I saturate the said absorbent *D*, through one of the openings *A*, with the medicated fluid I use for the inhaler, and 70 the medicated fumes are given off in the form of a dry gas when the stopper is removed and the inhaler applied to the affected parts of the patient, thus securing the desired effect upon the organs, which could not be so readily and 75 safely done by the direct application of the medicated fluid.

Ether or chloroform may be safely and effectually administered in the above manner, which is most beneficial and economical, no 80 waste being possible.

Fig. 6 is a cup of about one and one-fourth inches in diameter and is capable of being screwed to one of the openings *A* in the inhaler and held to a closed eye for the treatment 85 of inflamed eyelids and weak eyes. A cup about two inches in diameter may be screwed to one of the openings *A* and applied to any part of the patient where pain exists, this mode being more convenient than the application of mustard and other poultices. In 90 cases of sleeplessness, enlarged or inflamed nose, headache, catarrh, neuralgia, toothache, cold, influenza, or hay-fever the patient can readily remove the stopper and inhale through 95 the nose.

Fig. 7 is a throat-tube capable of being screwed to one of the openings *A* in the inhaler for use in the treatment of consumption, asthma, bronchitis, and lung and throat 100 affections, the end of the tube being passed into the throat through the patient's mouth.

Fig. 8 is a tube about four inches long and is capable of being screwed to one of the

openings A in the inhaler and is designed for use in treatment of the ear.

Fig. 9 shows a short pipe of vulcanite A attached to a rubber pipe c about twelve inches 5 in length. The pipe A is screwed to the second opening in the inhaler. B is a mouth-piece at the other end of the pipe c, through which the patient gently blows, the medicated remedy being thereby caused to pass into the 10 ear through the vulcanite tube shown in Fig. 8.

What I claim as my invention, and desire to secure by Letters Patent, is—

The medical inhaler consisting of a casing provided on one side with a recess and means 15 for securing a thermometer within said recess, the casing being provided on its sides with gauze-covered openings and means for attaching opposite said openings interchangeable tubes for the eye ear throat and mouth sub- 20 substantially as described and shown.

Dated this 22d day of May, 1897.

ELIZABETH ROWLAND.
